UNITED STATES PATENT OFFICE.

HENRY T. HAYDEN, JR., OF NEW YORK, N. Y., ASSIGNOR TO WARD LEONARD ELECTRIC COMPANY, A CORPORATION OF NEW YORK.

RESISTANCE DEVICE.

Application filed July 19, 1926. Serial No. 123,291.

This invention relates to electric resistors of the sheet metal type and to the method of constructing the same.

The principal objects of my invention are 5 to provide a resistor of this character having a continuous resistance element or conductor of improved form, and to provide an improved method of constructing such resistor wherein the continuous resistance 10 element is formed from a single sheet of metal with little or no waste of material. Further objects are to provide an improved resistor which is simple, light, strong and durable in construction, economical in cost 15 of construction and efficient in operation. Such a resistor may consist of a single suitably mounted resistance element or may comprise a plurality of such elements, each of which, with its mounting, forms a separate 20 resistance unit of the resistor, and a further object of my invention is to provide an improved resistor comprising a plurality of such units.

Other objects of my invention will appear 25 from the following description taken in connection with the accompanying drawing, wherein

Fig. 1 shows a sheet metal blank from 30 which a resistance element, employed in one form of my resistor, is made.

Fig. 2 is a side elevation, partly in section, of a resistor or resistor unit employing a resistance element formed from the blank shown in Fig. 1.

Fig. 3 is a sectional view taken on the line 3-3 of Fig. 2.

Fig. 4 is a view similar to Fig. 2, but showing a resistor having a resistance element of somewhat modified form.

Fig. 5 is a view similar to Fig. 1, but showing a modified form of sheet metal resistance element blank.

Fig. 6 is a side elevation of a modified resistor or resistor unit employing a resistance element formed from the blank shown in Fig. 5.

Fig. 7 is a partly diagrammatic top plan view of a resistor employing a plurality of the resistor units such as is shown in Figs. 2, 50 4 or 6.

The blank shown in Fig. 1 is formed of a flat sheet of resistance metal in which has been formed a series of parallel staggered slits 11, extending inwardly from opposite edges of the sheet and over-lapping one an-

other and thus forming a series of strips 12, each of which is joined at one of its ends to an adjacent strip at one side by a connecting portion 14, and at the other of its ends to an adjacent strip at the opposite 60 side by another connecting portion 14. The connecting portions 14 have openings 15 therethrough which are located in line with the slits 11 and the free ends of the end strips have terminal portions 17 formed 65 with openings 15, which are located in line with the outer edges of the end strips. The blank of the form shown in Fig. 1 may be readily made from a flat sheet of metal by stamping and cutting. 70

Referring to Fig. 2, 20 represents a zigzag resistance element formed from the blank shown in Fig. 1. To form the resistance element 20 each of the connecting portions 14 are turned so that they lie parallel with 75 one another and the axes of all of the openings which lie along each edge of the blank are in alignment. Thus, the connecting portions 14 along the bottom of the sheet and the terminal portions 17 may be given 80 a turn of 90° in a clockwise direction when viewed from the bottom of the sheet as shown in Fig. 1, and each of the connecting portions 14 at the top of the sheet may be given a turn of 90° in a counter clockwise direction when viewed from the bottom of the sheet. The result of turning the connecting portions and the terminal 85 portions in this manner is to twist each of the strips 12 to 180° as is indicated in Fig. 2. 90

The resistance element 20 when formed as above described, is mounted on two parallel metal rods 22 and 23, which extend respectively through the upper row of openings 15 and through the lower row of openings 95 15 in the resistance element 20, and are secured at their ends to supporting channel bars 21. The successive connecting portions 14 of each row are spaced from one another 100 and form the supporting rods by insulating sleeves 24, each of which is formed with a boss 26 which extends through the opening 15 into a recess or seat 27 formed in the adjacent sleeve. Each row or series of insulating sleeves and spaced connecting portions 14 is firmly held on the supporting rod by nuts or screw threaded washers 30, which are mounted on screw threaded portions 34 of the rods and bear against the end sleeves of the rows. Terminal clamps 35 110

are secured to the terminal portions 17 of the resistor and form circuit connections thereto. Clamps 35 comprise clamping members 38 and 39 which are adapted to be forced toward one another by bolts 40 and clamp between them the projecting parts of the terminal portions 17 of the resistance element. Members 38 and 39 are recessed at their inner ends so as to partially embrace the adjacent ends of the insulating sleeves 24.

In Fig. 4 I have shown a resistor having a somewhat modified resistance element 44, wherein each of the connecting strips 45 is formed with a longitudinal strengthening rib 46, and each of the strips are twisted through 90° at points beyond the ends of the ribs instead of being twisted throughout the length of the strip as in the form of resistance element shown in Fig. 2. The resistance element 46 is made from blank of similar form to that shown in Fig. 1, except that the blank has the ribs 46 stamped therein.

In the zigzag resistance elements shown in Figs. 2 and 4, successive strips are oppositely and equally inclined to the vertical. In the form of my invention shown in Fig. 6, alternate strips 50 are vertical and the remaining strips 51 are inclined to the vertical. It will be noted that in this form of resistor the distance between openings 15 at the opposite ends of a vertical strip 50 is somewhat less than the distance between the openings at the opposite ends of an inclined strip 51. To provide for this difference in the lengths of the strips as measured from the opening at one end to the opening at the other end, and also to insure the alignment of the openings at the lower ends of the strips and the alignment of the openings at the upper ends of the strips, when the resistor is bent into the form shown in Fig. 6, I employ a blank shown in Fig. 5 in which the openings along each side of the sheet are located on a line which is inclined to the normal of the slits 11. The slits 11 terminate in the sheet at points which lie on lines parallel to the lines joining the centers of the openings 15 and the side edges of the blank are preferably stepped as shown at 55 so that the connecting portions 56 which join the ends of the strips will have square edges. If desired however, the corners of the connecting portions may be rounded. The resistor shown in Fig. 5 is somewhat more compact than that shown in Fig. 2.

In Fig. 7, I have shown the manner in which a plurality of resistors such as that shown in Fig. 2 or 5 may be employed as resistance units to form a resistor of larger capacity. For connecting the several units together, I provide rods 60 which extend through openings 61 shown in Figs. 2 and 6, located in the sides of the channel bars 21

and nuts 63 serve to hold the channel bars in place on the rods. It will be understood that the rods 60 are carried by a supporting structure such as a car-body frame which thus forms a supporting means for the entire 70 resistor. Electrical connections between the several units of the resistor may be made as shown in Fig. 2.

The resistance element, when formed with connecting strips twisted and spread as above described, is provided with strips which will not be distorted, sag or expand to such degree that they will contact each other when heated to high temperatures by the electric current passing therethrough. 80 This construction of the conducting strips eliminates short circuiting of the resistance element at high temperature.

I claim:

1. The method of forming a resistor having a resistance element formed from a sheet of metal, having slits therein which divide the sheet into a series of strips and two rows of substantially flat connecting portions at the ends of the strips, the connecting portions at opposite ends of a strip respectively joining said strip to strips at opposite sides of said strip, which method consists in twisting the strips in such a manner that the connecting portions lie in parallel planes with the connecting portions of each row, spaced from one another and in alignment, and securing said connecting portions so spaced to two parallel supports.

2. The method of forming a resistor having a resistance element formed from a sheet of metal having slits therein which divide the sheet into a series of strips and two rows of connecting portions at the outer ends of the strips, the connecting portions at opposite ends of a strip respectively joining said strip to strips at opposite sides of said strip which method consists in twisting the strips in such a manner that the connecting portions of each row are spaced from one another in a direction normal to their faces, and all the connecting portions of each row are in alignment, and in mounting the said resistance element on a support which maintains the connecting portions so spaced.

3. The method of forming a resistor having a resistance element formed from a sheet of metal having slits therein which divide the sheet into a series of strips and two rows of connecting portions at the outer ends of the strips, the connecting portions at opposite ends of a strip respectively joining said strip to strips at opposite sides of said strip, which method consists in twisting each of the strips through a half turn so that the connecting portions of each row are spaced from one another in a direction normal to their faces, and all the connecting portions of each row are in alignment, and in mounting the said resistance element so formed on

a support which maintains the connecting portions so spaced.

4. The method of forming a resistor having a resistance element formed from a sheet of metal having slits therein which divide the sheet into a series of strips and two rows of connecting portions at the outer ends of the strips, the connecting portions at opposite sides of a strip respectively joining the said strip to strips at opposite sides of said strip and each of the connecting portions having an opening therethrough, which method consists in twisting the strips so that the connecting portions of each row are spaced from one another and the axes of their openings are in alignment, and in mounting said resistance element so formed on two parallel rods extending through said openings.

20 5. The method of forming a resistor having a resistance element formed from a sheet of metal having slits therein, which divide the sheet into a series of strips and two rows of connecting portions at the outer ends of strips, the connecting portions at opposite sides of a strip respectively joining the said strip to strips at opposite sides of said strip and each of the connecting portions having an opening therethrough in line with the slits which consists in twisting each of the strips through a half turn so that the connecting portions of each row are spaced from one another and the axes of their openings are in alignment, and in mounting said resistance element so formed on two parallel rods extending through said openings.

6. The method of forming a resistor having a resistance element formed from a sheet of metal having slits therein which divide the sheet into a series of strips and two rows of connecting portions at the outer ends of the strips, the connecting portions at opposite ends of a strip respectively joining the said strip to strips at opposite sides of said strip, which method consists in twisting the strips a half turn and supporting the connecting portions.

7. The method of forming a resistor having a resistance element formed from a sheet of metal having slits therein which divide

the sheet into a series of strips and two rows of connecting portions at the outer ends of the strips, the connecting portions at opposite ends of a strip respectively joining the said strip to strips at opposite sides of said strip, which method consists in twisting the strips substantially throughout the length of the strips and bringing each of the connecting portions in planes parallel to each other, and supporting each of the connecting portions at the respective ends of the strips in alignment.

8. A continuous resistance element of slotted sheet metal, said element having a zigzag form and comprising strips and connecting portions at the outer ends of the strips, the connecting portions along each side of the element being flat and facing one another in alignment and the strips being twisted.

9. A resistor comprising a continuous resistance element of slotted sheet metal, said element having a zigzag form and comprising strips and connecting portions at the outer ends of the strips, each of said connecting portions having an opening therein in line with the slits, the metal of said strips being twisted so that the connecting portions along each end of the strips face one another and are spaced from one another and the axes of their openings are in alignment, and supporting means extending through said openings.

10. A resistor comprising a continuous resistance element of slotted sheet metal, said element having a zigzag form and comprising strips and connecting portions at the outer ends of the strips, each of said connecting portions having an opening therein, said strips being twisted so that the connecting portions along each edge of the element are spaced from one another and the axes of their openings are in alignment, an insulated supporting rod extending through the openings at one edge of said element and a second insulated supporting rod, parallel to said first named rod, extending through the openings at the other edge of said element.
